Leopold S. Richards, of Attleboro, Mass.
Letters Patent No. 1.761, dated May, 19, 1863.

The schedule referred to in these Letters Patent and making part of the same.

2

Des 1761

To all whom it may concern:

Be it known that I, Egbert S. Richards, of Attleboro, in the Commonwealth of Massachusetts, have invented a new and original design for an ornamental chain; and I do hereby declare that the following is a full and exact description of the same, reference being had to the accompanying drawings making a part of this specification.

The purpose of the new design exhibited in the accompanying drawings is to relieve by the contrast of color the links of ornamental chain which are made of glass, jet, wood, vulcanized rubber or other similar materials and to present the appearance of inlaid work.

I therefore make the several links of this class of chains fluted and cause the channels to run spirally around the axes of the links as shown.

In each of these channels I place metallic wires a, a, a, of a contrasting color and connect these wires which may be made so as to resemble a cord, with the tops of the links b, b, at the ends.

The result will be a new design for this article of manufacture presenting the appearance of a skeleton metallic link, the body of which is of a contrasting color and enclosed within the metallic frame.

What I claim as new and desire to secure by Letters Patent, is:-
The ornamental design for the links of a chain herein described and represented in the accompanying drawings.
